A. R. ADAMSON.

MAGAZINE RIFLE.

APPLICATION FILED FEB. 20, 1911.

1,032,101.

Patented July 9, 1912.

UNITED STATES PATENT OFFICE.

AUGUST RUDOLPH ADAMSON, OF COLLINSVILLE, CONNECTICUT.

MAGAZINE-RIFLE.

1,032,101.

Specification of Letters Patent.

Patented July 9, 1912.

Application filed February 20, 1911. Serial No. 609,686.

To all whom it may concern:

Be it known that I, AUGUST R. ADAMSON, citizen of the United States, residing at Collinsville, in the county of Hartford and State of Connecticut, have invented certain new and useful Improvements in Magazine-Rifles; and I do hereby declare the following to be a full, clear, and exact description of the invention, such as will enable others skilled in the art to which it appertains to make and use the same, reference being had to the accompanying drawings, and to the letters and figures of reference marked hereon, which form a part of this specification.

This invention relates to new and useful improvements in magazine rifles and the object in view is to produce a simple and efficient device of this nature having various details of construction and combinations and arrangements of parts which will be hereinafter fully described and then specifically defined in the appended claim.

I illustrate my invention in the accompanying drawings, in which:—

Figure 1 is a vertical sectional view through a portion of a rifle. Fig. 2 is a top plan view. Fig. 3 is a sectional view. Fig. 4 is a detail perspective view of a breech block and Fig. 5 is a view in elevation of a hook adapted to hold the cartridges while being delivered singly to be inserted in the barrel. Fig. 6 is an enlarged detail view in side elevation of a portion of the device.

Reference now being had to the details of the drawings by letter, A designates a rifle barrel, B the stock, C the hammer, D the firing pin, E the trigger, F the hammer releasing lever mounted upon the pivot pin F'. N designates a breech block with a handle N', and M the magazine containing the spring M² and the follower M² adapted to be moved by the spring to throw the car-

tridges into proper position to be moved 45 forward into the barrel of the gun. All these features are of the usual construction common to the magazine rifle and for which no novelty is claimed.

In the side of the magazine is mounted 50 an angle plate J having pintles J' and a spring J² is fastened at one end to the marginal opening, as shown clearly in Fig. 5, and its other end to one end of the angle plate and serves to normally hold the plate 55 so that the free end thereof will be disposed partially across the magazine so as to allow the shells to pass out of the magazine and in position to be fed forward by the breech block into the barrel.

In operation, the cartridges are moved upward by the spring acting against the follower, the angle plate allowing the shells to be singly fed into positions to be advanced by the breech block. When a shell 65 has been fed forward, the angle plate will be thrown back with the spring and hold the remaining cartridges within the magazine in place.

What I claim to be new is:—

A magazine rifle having a magazine chamber, an angle plate having pintles at the opposite edges thereof journaled in the marginal edge of an opening in the wall of the magazine, a spring connected to one end 75 of the plate and its other end fastened to the marginal edge of said opening, said plate adapted to bear against the shells as they are pushed by the follower in the magazine in positions to be delivered to the 80 barrel.

In testimony whereof I hereunto affix my signature in the presence of two witnesses.

AUGUST RUDOLPH ADAMSON.

Witnesses:

ALBERT B. CASE,
FRANK A. COX.
